CYLINDER HEAD OF AN AIR-COOLED INTERNAL COMBUSTION ENGINE

BACKGROUND OF THE INVENTION

The present invention relates to a cylinder head of an air-cooled internal combustion engine with a pressure oil channel for the additional cooling of places in the cylinder head which are particularly subjected to thermal stresses.

With such a type of cylinder head, a groove for pressure oil is machined into the seating surface thereof in order to attain within this area a uniform temperature distribution. Untight or leaky places as a result of surface warping or surface distortion at the cylinder head flange are to be avoided thereby.

SUMMARY OF THE INVENTION

In contradistinction thereto, the present invention aims at intensively cooling by means of pressure oil the thermally maximal stressed area of the cylinder head, especially of high performance engines. This takes place according to the present invention in that the pressure oil channel passes over into a hollow space arranged on the inside of the cylinder head, at the interior walls of which are arranged cooling ribs.

A particularly effective heat transfer or heat removal is achieved in accordance with the present invention in that the cooling ribs, starting from wall parts of the hollow space that are particularly heated up, intermesh or interengage with one another in such a manner that in cooperation with a filler piece protruding into the hollow space a meander-shaped guidance of the cooling oil stream results.

Accordingly, it is an object of the present invention to provide a cylinder head for an air-cooled internal combustion engine which avoids, by simple means, the shortcomings and drawbacks mentioned hereinabove and encountered in the prior art constructions.

Another object of the present invention resides in a cylinder head of air-cooled internal combustion engines, especially of high performance engines in which the areas of the cylinder head that are subjected to maximum thermal stresses are effectively and intensively cooled.

A further object of the present invention resides in a cylinder head of an air-cooled internal combustion engine in which an efficacious heat removal is achieved by simple and relatively inexpensive means.

Still another object of the present invention resides in a cylinder head of an air-cooled internal combustion engine which is simple in construction, easy to assemble and reliable in operation for the intended purposes.

Still a further object of the present invention resides in a cylinder head for an air-cooled internal combustion engine which assures effective cooling without the need for any additional supply pump or oil cooler other than those already necessitated for the lubricating circulatory system.

A further object of the present invention resides in a cylinder head of an air-cooled internal combustion engine which is provided with an approximately meander-shaped pressure oil channel effectively avoiding dead spaces for the cooling oil.

These and further objects, features, and advantages of the present invention will become more obvious from the following description when taken in connection with the accompanying drawing which shows, for purposes of illustration only, one embodiment in accordance with the present invention, and wherein:

FIG. 1 is a partial cross-sectional view through an installed cylinder head of an air-cooled Diesel engine in accordance with the present invention, taken along line I-I of FIG. 2; and

FIG. 2 is a partial cross-sectional view through the cylinder head of FIG. 1, taken along line II-II of FIG. 1.

Referring now to the drawing wherein like reference numerals are used throughout the two views to designate like parts, reference numeral 11 designates in both views the cylinder head which is mounted on a cylinder 12 and is

covered by control housing 13 enclosing the conventional control devices, such as rocker arms, etc. A conventional seal is interposed between the cylinder head 11 and the control housing 13. Clamping or tightening bolts 16 starting from the control housing 13 extend through through-bores 17 (FIG. 2) in the cylinder head 11 and are guided through corresponding apertures at the cylinder 12 and connect these structural parts with the crankcase (not shown).

An inlet channel 18, an exhaust channel 19 and a bore 20 for the accommodation of an injection nozzle (not shown) are arranged in the cylinder head 11. Ribs 21, 22 and 23 extend from the cylinder head 11 for the purpose of air-cooling. Through-bores 24 and apertures 25 for the pushrod protective tubes 26 are provided in the ribs 22.

15 The first partial section 27 (FIG. 1) of a pressure oil channel terminates in a hollow space 28 and is continued in a further partial section 29 from which branches off at right angle in the upward direction the partial section 30. A channel 31 in the control housing 13 adjoins the partial section 30. A closure screw 32 closes the end of the partial section 29. Threaded connecting nipples 33 and 34 are disposed at the beginning of the partial section 27 of the channel and at the end of the channel 31, respectively.

25 The hollow space 28 is arranged in the cylinder head 11 above the web between the inlet channel 18 and the exhaust channel 19. Cooling ribs 36 and 37 start from the bottom 35 (FIG. 1) of the hollow space 28. The cooling ribs 36 extend in part from the lateral wall 38 up to the lateral wall 39 (FIG. 2) 30 of the hollow space 28. The cooling ribs 37 are connected only with the lateral wall 39 and are constructed higher. A stepped-down or shouldered-off filler piece 41, arranged at the bottom side 40 of the control housing 13, extends up to the upper edges of the cooling ribs 36 and 37 and closes off the hollow 35 space 28 in the upward direction. The filler member 41 may, as shown in the drawing, be connected in one piece with the control housing 13 or may be secured at the same time, for example, by screws or bolts.

The illustrated cooling oil circulatory system of the cylinder head 11 is connected in parallel to the conventional lubricating oil circulatory system (not shown) of the internal combustion engine. A separate supply pump and a further oil cooler can be saved as a result thereof. The supply line branching off from the lubricating oil circulatory system is connected with the connecting nipple 33 while the return line is connected to the connecting nipple 34. During operation, the pressure oil flows through the partial section 27 of the channel into the hollow space 28. The cooling ribs 36 and 37 arranged transversely to the main flow direction, together with the stepped filler piece 41 extending up to the upper edges of the cooling ribs, impose upon the cooling oil stream a meander-shaped path both in a parallel plane to the bottom 35 of the hollow space 28 as also in a parallel plane to the lateral wall 39. Dead spaces, in which the cooling oil can collect and dam up, are avoided thereby. It is possible in this manner to remove or carry off a maximum amount of heat from the parts of the cylinder head which are particularly subjected to thermal stresses, i.e., above all from the web between the inlet channel 18 and the outlet channel 19. After leaving the hollow space 28, the pressure oil flows through the partial sections 29 and 30 into the channel 31 within the control housing 13, from where it is returned again to the lubricating oil circulatory system by way of the return line.

65 While we have shown and described only one embodiment in accordance with the present invention, it is understood that the same is not limited thereto but is susceptible of numerous changes and modifications as known to a person skilled in the art. For example, instead of one hollow space equipped with cooling ribs, also several hollow spaces suitably provided with cooling ribs may be connected in series and/or in parallel to each other with the pressure oil channel in the cylinder head.

70 Thus, it is obvious that the present invention is susceptible of numerous changes and modifications and we therefore do not wish to be limited to the details shown and described

herein but intend to cover all such changes and modifications as are encompassed by the scope of the appended claims.

We claim:

1. A cylinder head for an air-cooled internal combustion engine provided with air-cooling means and a pressure oil channel for the additional cooling of places in the cylinder head that are particularly subjected to thermal stresses, characterized in that during engine operation a pressurized oil stream flows through the pressure oil channel and passes over into a hollow space provided on the inside of the cylinder head, and cooling rib means are arranged at the inner walls forming said hollow space.

2. A cylinder head according to claim 1, further comprising filler means extending into the hollow space, the cooling rib means so engaging with one another that in conjunction with said filler means an approximately meander-shaped guidance of the cooling oil stream results.

3. A cylinder head according to claim 2, wherein said cooling rib means start from those wall parts that are particularly subjected to heat stresses.

4. A cylinder head according to claim 3, wherein said cooling rib means engage alternately with each other in such a manner that said meander-shaped guidance for the cooling oil stream results.

5. A cylinder head having a control housing mounted on the cylinder head according to claim 4, wherein said filler means is arranged at the bottom side of the control housing.

6. A cylinder head provided with a web between its inlet

channel and its outlet channel according to claim 5, characterized in that said hollow space is arranged above said web.

7. A cylinder head according to claim 6, wherein the engine includes a lubricating circulatory system, and wherein said pressure oil channel is operatively connected with said lubricating oil circulatory system.

8. A cylinder head provided with a web between its inlet channel and its outlet channel according to claim 1, characterized in that said hollow space is arranged above said web.

9. A cylinder head according to claim 1, wherein the engine includes a lubricating circulatory system, and wherein said pressure oil channel is operatively connected with said lubricating oil circulatory system.

10. A cylinder head according to claim 1, characterized in that said hollow space extends through the cylinder head only within the areas thereof subjected to very high thermal stresses.

11. A cylinder head according to claim 10, characterized in that said hollow space extends through the cylinder head only within the area thereof disposed between its valve channels.

12. A cylinder head according to claim 1, characterized in that said chamber is limited to the area between the valve channels of the cylinder head.

13. A cylinder head according to claim 1, characterized in that said oil channel is of relatively small cross section compared to the cross section of the cylinder head in a plane extending through said oil channel.
